UNITED STATES PATENT OFFICE.

NANNIE G. DAVIS, OF WASHIINGTON, DISTRICT OF COLUMBIA.

DESIGN FOR A SPOON.

SPECIFICATION forming part of Design No. 21,312, dated January 26, 1892.

Application filed December 31, 1891. Serial No. 416,732. Term of patent 3½ years.

To all whom it may concern:

Be it known that I, NANNIE G. DAVIS, a citizen of the United States, residing at Washington, in the District of Columbia, have invented and produced a new and original Design for Spoons, of which the following is a specification, reference being had to the accompanying drawing, forming part thereof.

The figure represents a face view of a spoon having thereon a representation of my design. The leading feature of my design consists in a representation of the Cleveland family, consisting of Ex-President Cleveland, his wife, and baby girl. The head of Mrs. Cleveland is arranged in an oval frame, connected by a neck to another oval frame, with the head of Mr. Cleveland and a view of their baby Ruth in the bowl of the spoon, with a gradu-

ally-tapering ornamental handle connecting the frames with the bowl. At the upper end 20 of the spoon A is arranged a representation of the head of Mrs. Cleveland, placed in an oval frame B, with foliage projections, and connected to a highly-ornamented neck C, which has attached to it another oval frame D, containing a picture of Mr. Cleveland. In the bowl E of the spoon is placed a representation of the baby Ruth, the infant daughter of Mr. and Mrs. Cleveland.

What I claim is—

The design for a spoon, herein shown and described.

NANNIE G. DAVIS.
